DESIGN FOR A DRESS

Concetta Jaccarino, Brooklyn, N. Y.

Application January 2, 1941, Serial No. 97,782

Term of patent 3½ years

To all whom it may concern:

Be it known that I, Concetta Jaccarino, a citizen of the United States, residing at 1122—71st Street, Brooklyn, New York city, in the county of Kings and State of New York, have invented a new, original, and ornamental Design for a Dress, of which the following is a specification, reference being had to the accompanying drawing, forming part thereof.

Figure 1 is a front view of a dress, showing my new design; and

Figure 2 is a rear view of Figure 1.

The characteristic feature of my design resides in the combination on the dress disclosed of cartridge pleating on the front of the blouse portion and skirt pockets, in association with the full length stitched front panel as shown.

I claim:

The ornamental design for a dress, substantially as shown and described.

CONCETTA JACCARINO.
